INVENTOR:

UNITED STATES PATENT OFFICE

LESTER C. GUNDERMAN, OF PITTSBURGH, PENNSYLVANIA

GAME

Application filed May 15, 1926. Serial No. 109,260.

This invention is for a game or device of the type in which objects move in a circular course around a circular track furnishing amusement and recreation in its use.

5 The object is to provide a game of the general class which is of such construction that the rotation of the track causes the objects to travel at a less rate of speed than the track.

A further object of the construction, comprising a base above which is mounted a revolvable frame having wheels mounted thereon, and supporting a circular track which is free to revolve thereon.

15 A further object of the construction, is means for positively revolving the frame above the base.

A further object of the construction is to provide a frame to guide the objects around the track.

20 In order that the invention may be readily understood, reference is made to the accompanying drawing.

Fig. 1 is a plan view of the game, having a section of the track broken away showing part of the rotating frame and means of rotating the same, and one form of racing objects.

Fig. 2 is a fragmentary section on line A—A in Fig. 1.

30 Fig. 3 is a fragmentary section on line B—B in Fig. 1, and shows one form of racing objects to move around the track.

Fig. 4 is a side view of one form of members connecting the objects to the frame.

35 Fig. 5 is a fragmentary sectional view of a modified form of moving objects.

Fig. 6 is a top view of the modified objects.

40 Fig. 7 is a plan view of the game, having a section of the track broken away showing part of the rotary frame and the positive means for rotating the frame and a modified form of racing objects.

Fig. 8 is a section on line C—C in Fig. 7.

45 From the above descriptions it will be seen that the wheels 10 have a rolling contact on the base 8 and are journaled in the frame 12 which is centrally pivoted on the post 9, also the track 15 being rotatably anchored on the post 9 and supported on the wheels 10; the

rotating of the track 15 will cause the wheels 10 to roll on the base 8, the frame 12 being supported on the axles of the wheels 10 will rotate at a much less speed than the track 15; the objects being anchored on the frame 12 will also be rotated at a much less speed than the track 15.

The game comprises a base 8, upon which is mounted a post 9, supported on the base 8 are wheels 10 which partly extend through openings 11, in the frame member 12. The frame being loosely mounted over the post 9, lugs 13 are partly punched out of the frame and bent backward over the wheel axles to hold the wheels 10 in alinement. Surrounding the post 9 and rotatably attached thereto is a stem 14, supported on the wheels 10 and attached to the stem is a track 15, one end of each of the connecting members 16 is mounted on the outer edge of the frame 12, near the opposite end of connecting members are mounted racing objects 17, which are in the form of miniature cars. The ends of the connecting members terminate in a point 18 to indicate the scoring numerals 19 on the track 15. The lugs 20 which are used for attaching one form of racing objects, are partly punched out of the frame and bent backward over the connecting member.

In Figs. 5 and 6, is shown a modified form of racing objects 21, which are in the form of miniature aeroplanes, the connecting members 29 extending upward and inward, forming the support for the objects 21 and the end 22 act as pointers to indicate the scoring numerals.

A wheel 30 supported on the base 8 and journaled in the connecting members 29 support the rotating objects and steady the objects in their travel around the disc track 15.

In Figs. 7 and 8 is shown another form of objects 23 which are made in the form of a series of points 24 and are mounted on the ends of vertical spindles 25, mounted on the lower end of the spindles 25 are wheels 26 which engage with the raised portion 27 of the base 8, this gives the pointers a revolving motion when traveling around the disc 15.

The pointers 24 are provided with numerals 28 which are used in conjunction with the nu-

merals 19 in counting the scores of each play.

In order that the frame 12 will positively rotate about the post 9, I have shown in Figs. 7 and 8, a gear 31 mounted on the base 8 by the pivot post 9, a gear 32 is attached to the underside of the track 15, by the stem 14, and on each side of the frame 12 is a gear 33 and 34 connected together by a shaft 35. The rotation of the gear 32 which engages and rotates the gear 34 which also rotates gear 33 through shaft 35, the gear 33 engaging the gear 31, will positively revolve the frame about the post 9.

In playing games with the device the objects 17, 21 and 23 rotate around the track 15, at a less rate of speed than the track, each of the objects being of a different color to be readily distinguished one from the other.

The game is suitable for three players, each player making his choice of the rotary objects, each player then spins the track in turn and as the objects come to rest, the pointer will indicate the scoring numerals each player's score being advanced according to the numerals indicated by the pointers until total points of 100 is reached, or a total number of points pre-arranged by the players.

From the above description it may be apparent that I provide a game of the character described which possesses the feature of advantages pointed out, and I wish it to be understood that what I have described and claimed now seems to be the preferred embodiment of the invention. I reserve the right to make all changes falling within the spirit and scope of the appending claims.

I claim:

1. A game comprising a base, a post on the base, a frame loosely fitted over the post, 40 wheels journaled in the frame having rolling contact on the base, a disc having a central stem rotatably fitted over the post whereby it is revolvably mounted on the wheels, miniature objects mounted on the frame and adapted to travel in a circular manner on the track.

2. A game comprising a base, a post on the base, a frame surrounding the post and mounted on wheels, a circular track rotatably fitted over the post, and having rolling contact on said wheels, racing objects mounted on the frame.

3. A game comprising a base, a post on the base, a frame rotatably anchored on the post, wheels supported on the base and journaled in the frame, a circular track having rolling contact on said wheels and rotatably anchored on the post, racing objects anchored on the frame.

4. A game comprising a base, a post on the base, a frame rotatably anchored to the post, wheels journaled in the frame and supported on the base, a disc engaging the wheels and rotatably anchored on the post, miniature objects anchored to the frame.

5. A game comprising a base, a post on the

base, a disc having numerals thereon pivoted on the post, a frame rotatably anchored to the post, wheels engaging the base and supporting the disc, said wheels journaled in the frame for effecting rotation of said frame when the disc is spinning, racing objects anchored to the frame.

6. A game comprising a base, a post on the base, a circular track pivoted on the post, a frame rotatably anchored to the post, a connecting member anchored on the frame, objects anchored on the connecting members, wheels journaled in the frame, engaging the base and supporting the track constituting means to rotate the track at a greater speed than the objects for effecting rotation of said frame when the disc is in motion.

In testimony whereof I affix my signature.

LESTER C. GUNDERMAN.
